G. W. LISK

SPRAYER

Filed Oct. 23, 1924

^{Inventor}
George W. Lisk

By Watson E. Coleman
Attorney

UNITED STATES PATENT OFFICE.

GEORGE W. LISK, OF CLIFTON SPRINGS, NEW YORK.

SPRAYER.

Application filed October 23, 1924. Serial No. 745,448.

To all whom it may concern:

Be it known that I, GEORGE W. LISK, a citizen of the United States, residing at Clifton Springs, in the county of Ontario and State of New York, have invented certain new and useful Improvements in Sprayers, of which the following is a specification, reference being had to the accompanying drawings.

10 This invention relates to certain improvements in sprayers and has relation more particularly to a device of this general character especially designed and adapted for use in connection with liquid disinfectant or other liquid adapted to be distributed in a comminuted condition, and it is an object of the invention to provide a novel and improved device of this kind comprising a liquid tube and an air tube together with means for effectively maintaining adjacent end portions of said tubes in requisite assembled relation.

25 Another object of the invention is to provide a novel and improved device of this general character wherein the air tube or mouth piece has disposed therethrough a bore substantially elliptical in cross section and of the same dimensions from one end to the other.

30 It is also an object of the invention to provide a device of this general character with a novel and improved bracket adapted to engage the adjacent ends of the liquid tube and the air tube for maintaining said tubes in desired relation and in a strong and effective manner.

35 The invention consists in the details of construction and in the combination and arrangement of the several parts of my improved sprayer whereby certain important advantages are attained and the device rendered simpler, less expensive and otherwise more convenient and advantageous for use, as will be hererinafter more fully set forth.

40 The novel features of my invention will hereinafter be definitely claimed.

45 In order that my invention may be the better understood, I will now proceed to describe the same with reference to the accompanying drawings, wherein:-

50 Figure 1 is a view in perspective illustrating a spraying device constructed in accordance with an embodiment of my invention;

55 Figure 2 is a view in perspective of the bracket as herein disclosed unapplied;

60 Figure 3 is a view in perspective of the bracket partly completed;

65 Figure 4 is a view in plan of the blank from which the bracket is formed.

70 As disclosed in the accompanying drawings, 1 denotes a liquid or lifting tube of desired dimensions and which is adapted to be inserted in the well-known manner within the liquid to be distributed or sprayed. Associated with the upper or outer end portion of the tube 1 is the air tube or mouth piece 2. This tube or mouth piece 2 is flattened from end to end in a manner to provide a substantially elliptical bore. This bore is also of substantially the same dimensions through its length. By this form of tube or mouth piece its application within the mouth of the user is facilitated and at the same time a more effective blast of air may be forced therethrough. When in assembled relation the adjacent ends of the tubes 1 and 2 are arranged with the upper or outer end of the tube 1 at substantially the axial center of the tube or mouth piece 2.

75 As herein disclosed, the adjacent end portions of the tubes 1 and 2 are rigidly maintained in desired assembled relation through the medium of the bracket B. This bracket B, as herein disclosed, is formed from an elongated blank 3 having its extremities correspondingly beveled, as at 4. The end portions of the blank 3 are bent back to overlie the intermediate portion of the blank 3, as is particularly illustrated in Figure 3, with the beveled extremities in close relation one to the other. The bend 5 for one of the return portions 6 is enlarged to provide a tube or barrel which is snugly engaged with the upper or outer end portion of the tube 1 while the bend 7 for the second return portion 6 is formed into the relatively broad sleeve to receive the discharge end portion of the tube or mouth piece 2.

80 It is to be understood, however, that after the blank has been formed as illustrated in Figure 3 the intermediate portion of the blank proper is bent or folded along a line between the opposed beveled edges 4 to bring the sleeve 7 above the barrel 5 with the bore of the sleeve 7 substantially perpendicularly related to that of the barrel 5.

85 After the tubes 1 and 2 have been properly engaged with the bracket B, suitable pres-

sure is brought upon the bracket B to cause the barrel 5 and the sleeve 7 to have close contact with the tubes 1 and 2 whereby said tubes are rigidly maintained in desired assembled relation.

In forming the bracket and also pressing the same into applied or working position it is to be understood that special tools are employed but as these tools form no part of the present invention it is thought that a detailed description and illustration thereof is unnecessary.

By connecting the tubes 1 and 2 by a bracket in accordance with the invention as herein disclosed, the use of solder is avoided and thereby the disadvantages incident to such use is eliminated. Furthermore, a sprayer is provided which is of materially increased strength and durability and which 20 may be employed to the best advantage.

From the foregoing description it is thought to be obvious that a sprayer constructed in accordance with my invention is particularly well adapted for use by reason of the convenience and facility with which it may be assembled and operated, and it will also be obvious that my invention is susceptible of some change and modification without departing from the principles and

spirit thereof and for this reason I do not wish to be understood as limiting myself to the precise arrangement and formation of the several parts herein shown in carrying out my invention in practice except as hereinafter claimed.

I claim:—

A spraying device comprising a liquid tube, an air tube, and a bracket for connecting the adjacent end portions of said tubes, said bracket being formed from an elongated flat strip of material having its opposite end portions bent back to overlie the intermediate portion of the strip, the extremities of said returned portions being correspondingly beveled, the intermediate portion of the strip being folded along the line between the opposed beveled edges to bring the bends for the returned portions in substantially perpendicular relation, the bend for one of the returned portions being enlarged to provide a barrel to snugly receive an end portion of the air tube, the bend for the second returned portion being formed into a sleeve to snugly receive an end portion of the liquid tube.

In testimony whereof I hereunto affix my signature.

GEORGE W. LISK.
